Iron Structure.

Nº 11,500,

Patented Aug. 8, 1854.

A. J. Saxton,

Iron Structure.

N° 11,509.

Patented Aug. 8, 1854.

UNITED STATES PATENT OFFICE.

AMOS J. SAXTON, OF BROOKLYN, NEW YORK.

MODE OF CONSTRUCTING IRON BUILDINGS.

Specification of Letters Patent No. 11,509, dated August 8, 1854.

To all whom it may concern:

Be it known that I, AMOS J. SAXTON, resident of the city and county and State of New York, have invented a new and improved 5 method of preparing for erection and erecting iron fireproof and other buildings without the use of rivets, screws, bolts, or nails; and I do hereby declare that the following is a full, clear, and exact description of the 10 same, reference being had to the annexed drawings, marked Figures 1 to 30, inclusive, like letters referring to similar parts in said figures.

Fig. 1 is a front elevation and Fig. 2 a 15 plan of the building composed of iron beams, columns or post and studs &c. as a frame work and Fig. 3 is a skeleton frame of an iron building, showing a part of the ashlers and window frames &c. set, which are secured to 20 the frame by my new method showing the improved manner of securing the iron plates which form the exterior and interior sides or walls of the building to the iron frame.

A, A, A, &c., Figs. 2 and 3, are iron columns, post, or studs, &c., formed substantially as shown in Figs. 2 and 3 and are shown on an enlarged scale by Figs. 7, 9, 25 10, 11, 12, 13, 15, 16, and in sections in 17, and 20, No. 16, &c.

B, B, B, &c., Figs. 2 and 3 are the horizontal beams and cross beams shown on an enlarged scale by Fig. 6, No. 2, repeated, &c., and in sections under Figs. 10 and 30 12, &c.

The post or studs A, A, A, &c., and the beams B, B, B, &c., form the main frame of the building resting on a proper foundation of masonry or otherwise. The partitions being also framed of studs and beams 35 in the same manner when desirable.

The columns, post, or studs, A, A, A, &c., and the beams, B, B, B, &c., are secured to each other by the method shown on an enlarged scale in Figs. 6 and 17, No. 13. The 40 main beams B, B, B, &c., and the girders are so shaped, on the ends and other parts where joints are required so as to form the double mortise and tenons shown in the drawings, into which the ends of the post or 45 studs fit being made of the tenon shape shown in the compound ex. and star joints shown by Figs. 6 and 17 by No. 13, and in the compound angular joint, Fig. 7 in sections marked No. 3, repeated, &c. The compound intersectional and interlocking ex. 50

joint No. 2, shown at Fig. 6, (repeated), is used to fasten the girders of the first story or foundation girders to each other; when united with the compound angular joints forms the compound star joint shown in 60 sections by Figs. 6 and 17, Nos. 13. Compound, angular joint No. 3 is used to fasten the corners of the frame of the building together, and is shown by Fig. 7, No. 3, in four forms of geometrical sections marked A, 65 B, C, and D, repeated. Compound joint No. 4, Fig. 8, is used to fasten the rafters, and purlins to the main frame of the building. The rafters are shown by the letters D, D, D, &c., and the purlin or stays by the 70 letters E, E, E, &c., compound joints No. 5, Fig. 9, is used to fasten the partitions to the frame of the building horizontally, &c. Compound joints No. 6 Figs. 10 are used for fastening or holding the cross partitions to 75 the frame of the building and to each other horizontally &c. Compound joints No. 7, Fig. 11, show the method of fastening the door frames of the interior of the building to the partition so as to allow the doors to slide or roll into or between the sections of 80 the partitions on their ways K, K, K, K, &c.

On the ways is shown a section of the door by Fig. 24. Compound joint No. 8, Figs. 12, represents the manner of fastening the upper 85 ceilings to the under side of the cross beams and girders &c. so as to make a plain or ornamented finish, &c.

Compound intersectional joints No. 9, 90 Figs. 13, show the manner of connecting the ornamental cornice and ceilings to the studs or columns on the inside of the buildings, &c.

Compound interlocking joints No. 10, 95 Figs. 14 (repeated), are the geometrical sectional parts of the ashlers showing the different methods of connecting or interlocking the ashlers or wall plates at the ends of the different sections, and different keys used for that purpose.

The ashlers are marked by the letters C, 100 and C' and in the compound interlocking joint No. 10, Fig. 14, and in the interlocking angular miter joint No. 10, Fig. 14, the sections are marked A, and B, that interlocks and the key C' that holds them together. 105 The joint that holds the miter sections together is marked by the letters s² and s³.

Compound joint No. 11, Fig. 15, is used for the purpose of connecting two columns or posts or two girders or cross beams in 110

such a manner as to form but one interlocking angular joint. This joint is shown on the margin on a large scale, Figs. 15 and No. 11 (repeated), in some of its forms.

5 Compound joint No. 12, Fig. 16, shows the method of fastening the exterior door columns to the frame of the building.

10 Compound star joint No. 13, Fig. 17, is used for the purpose of connecting two columns or posts and two girders or cross beams in such a manner as to form but one interlocking joint and is shown in sections, Fig. 6 (repeated).

15 Compound intersectional lap joint No. 14, Fig. 28. This lap joint is used for joining together different sections of the girders when it is necessary to extend them.

20 Compound intersectional and interlocking lap joint for post, &c., No. 15, and Fig. 29, shows the manner oflapping the posts or columns when it is required to extend them. The keys are marked *a* and *b*.

25 Compound union basement joint, Fig. 20, No. 16, shows in section several methods of connecting the girders and cross beams of a building with column, post, or studs. The girder is cast in sections and then formed into a hollow square and united firmly together by the interlocking sectional and 30 dowel joints *x*, and *y*, as shown connecting the upper side (*a*), with the undersection (*c*), and the two side sections (*b*) and (*d*), with the other parts in connection with the end dowels of section F, and F¹. The upper section (*a*) has two mortises cut into it 35 as shown at A, and B. Into the mortise A, a column or cross beam may be framed; and into the mortise B a stud or post interlocked by the foot of the tenon and are kept in 40 their places by the keys or wedges as shown in the sections D¹ and E¹ marked *e*, *i*.

45 The single joints of the cross beams connecting the girders to each other and to the foundation girders are of different shape, one from the other with different tenons and 50 mortises to suit or fit each other as shown on the ground plan, Fig. 2, and by Nos. 1, 2, 3, 4, 5, 6, 7, &c. They are used to keep the girders firmly in their places and to prevent 55 them from warping and twisting. Those of the first class are marked B, No. 1. Those of the second class are marked B, No. 2. Those of the third class are marked B, No. 3. Those of the fourth class are marked B, No. 4, &c. The cross beams are also used to lay 60 the floors or iron tessellate with glass or marble tiling or when that is used in place of common floors and for giving strength and durability to the buildings. They are used for the same general purpose on each 65 story as shown at Figs. 2 and 3. The mortises in the girders and the tenons of the posts are also marked to correspond with the number of class of cross beams to be used in connection with them.

The stringo or binding joints as shown at S, Figs. 4 and 5, on the ashler are used to secure the ashler or building plates to the columns post, or studs. The columns post or studs have strios (as shown at S') or 70 chamfer or groove cut or cast into the face or side of the columns, post, or studs on the exterior and interior sides of each which together are used to secure the ashler or building plates to the frames of the building as described and shown at Figs. 2, 3, 9, 10, 12 and 15. The long stringos or binding joints are shown at Figs. 4 and 5, by the letter *s*. The strios on the columns or post are marked S', repeated. The short 75 stringos or binding joints which are cast or formed on the back or inside of the ashler or inside plates which fit into the strios or grooves of the ashler, columns, post or studs are marked C², and the points where the stringo C² enters the studs A, A, A, &c., is marked on the studs *a*', *a*', as shown at Figs. 12 and 15. The openings are enlarged at certain intervals to admit the stringos of the ashlers or plates so that the ashler 80 may be moved up and down in the strios or grooves of the post or columns, &c. This method with the modifications are used for both the exterior and interior plates of the wall and serves to hold them firmly to the 85 vertical columns or posts, &c.

To secure the ends of the ashlers or plates to each other I use an interlocking joint shown on the end of the ashlers into which the key fits as shown at Figs. 4, 5, and 14. 90 The ends of the plates have alternate tenons and mortises of the interlocking shape which interlock with each other as drawn and shown at Figs. 4, 5 and 14. On these tenons a projection or strios are formed as 95 shown at Figs. 4, 5 and 14, into which on each side the edge of the spheroid or wedge shaped keys C⁵ fits firmly binding the end of the ashlers or plates to each other as shown at Figs. 4, 5 and 14. The ashler as 100 shown at section O, Fig. 5, is hollowed on the inside to one third of the thickness as shown for the purpose of making ashler light.

To unite the exterior and interior plates 105 more firmly to each other and to prevent them from springing out of the line of the front, I form at suitable distances between the studs on the back or inside of the plates, strios containing a groove or slide one opposite to the other into which short tie bars with stringos, on each end are inserted which hold the plates so as to make a firm connection between the opposite plates as shown at Fig. 29, letter G.

115 On the basement courses or any other where it is desirable to make a chancel between the plates as shown at Figs. 1, 3, 4, and 29, the upper edge of the lower plate is formed so as to fit the grooved edge of 120 130

the upper plate leaving a channel as at *c*' in Figs. 1, 3, 4 and 29, as the constructor may desire. The joints in the latter case being made flush as shown in Figs. 1, 3, 5, and 29.

Figs. 9, 10, represent in plan the method of forming the joints for the fitting of the casing of the windows by the same method of mortise and tenons, the form of the 10 vertical studs being adapted to such purposes.

Fig. 27 represents the roof truss in elevation with the principal rafters or tie beams. It is curved in the drawing but 15 may be made in any other form to suit the convenience of the constructor. *D*, *D* are the rafter, *E*, *E*, *E* &c. are sections of purlins secured to the rafters by the interlocking and intersectional joints as shown at 20 Figs. 8, and 27. *I*, *I*, are the tie beams.

Fig. 27 shows the iron sash bars *E* *E*, which are used for sustaining the roof tiles and for giving additional strength to the 25 roof. The tiles are secured to them by a cement adapted for that purpose which holds them firmly in their places.

Fig. 30, represents the method as applied to forming an iron truss or frame for the floor. The present drawings being more 30 particularly adapted to the use of malleable glass tiles. The iron tessellate bars for the tiling of the floors is shown in section by Fig. 30. The tiling are secured to the bars in the same manner as described in Fig. 27.

35 In Fig. 30 section *A*, 1, shows the iron tessellate resting on the cross beams which is composed of light iron bars running diagonally across the cross beams which are fastened into a cast or wrought iron frame 40 which is made to intersect the girders by a half lap of the frame but not shown. The tiling is shown in section *B*, 1. The rafters, purlins and other parts of the frame are of iron and are joined to each other by mortises, tenons, single and compound joints 45 with interlocking, intersectional, stringos, strios, sagittate and spheroid keys &c., shown in general plan at Fig. 3. After the plates which form the wall are secured to these

50 places on the frame to a proper height, I fill up the openings between the wall plates with any well known compound (that will act as a non conductor of heat) which may be used in combination with the construction and erection between the exterior and interior plates where it forms an additional support to the building. To protect the interior or exterior surface of the plates from oxidation, I paint them with sufficient number 55 of coats of paint or I apply a process of galvanizing or marbleize or crystallize them, before their erection giving them the appearance of marble, wood, or stone as may be desirable. By this method of joining the points or sectional parts of the frame

by my single and compound intersectional interlocking angular joints with all or any of the described ashler or plate joints for the exterior and interior walls &c. for the building. And by the use of the various 70 keys which are used to hold the foot of post columns or studs, &c. the use of rivets, screws, and bolts and nails is not required.

The different keys are shown in Figs. 4, 5, 9, 10, 11, 12, 14, 15, 16, 18, 19, 20, 21, 22, 75 and 23 &c. These keys in Figs. 9, 10, 11, 12, 19, 20, 21, and 22, are marked by the letters *a*, *e*, *i*, *o*, *u*, and *w*, *v*.

The tenons of the post or studs and the corresponding mortises and the keys shown 80 in Figs. 9, 10, 11, 12, &c. are marked by the same letters. The girders, post, studs, or cross beams may be cast hollow, square, round, or angular as may be required. The joints are all fitted or planed by hand or by a machine adapted for that purpose. The manner in which I secure the several points or parts of the building frame and the plates to each other is simple. It is also evident 85 that mortises and tenons, simple and compound joints may be replaced by other regular or irregular joints which will answer the same end. It is also evident that this method is not confined to any particular size or form of frame, or plate, as various sizes and shapes may be given to them which would answer the same general purpose, and various devices for ornamental effect may be used.

90 The kind of metal to be used is not limited to cast or wrought iron as malleable glass or any other material of similar tenacity would answer the purpose.

95 Thus it will be seen that any class or size of building may be erected and secured in 100 any of the sectional points by my improved joints on my plan in all or any of the component parts by my improved method of building first class substantial iron frame fire proof houses, stores, &c. in one half of 105 the time occupied in erecting brick or stone buildings; and one fourth of the cost will be saved by the constructor.

110 I do not claim to have invented the mortises, tenons, lugs, grooves, chamfers, common keys; or any simple dovetail joints; as I am aware that they have been used before; but

115 What I do claim as my invention and improvement and desire to secure by Letters 120 Patent is—

125 1. The method, mode, manner or process of connecting and combining all the different joints by all or any of the improved joints so arranged at all of the different 130 points by all or any of the different joints as when joined by the different joints at the sectional points as herein set forth and substantially described; the use of screws, rivets, bolts or nails is not required in the erec-

tion of iron frame fire proof or other buildings.

2. I claim the method mode or process of erecting iron fire proof and other buildings and of uniting or connecting each substantial part to each other or of connecting them at all of the sectional points by the different joints as described without the use of screws, rivets bolts or nails, as herein set forth and substantially described.

3. I claim the method, mode, or manner of so arranging and combining the different points of the columns post or studs, girders,

beams, ashlers and interior plates or any of the sectional parts of the buildings with 15 the different joints so combined in such a manner as when the different joints are properly united and combined with the different joints in all of the sectional parts, they form a substantial iron frame fire proof 20 or other buildings as substantially described in all of the different combinations.

AMOS J. SAXTON.
